FURNACE DOOR FRAME

Leland H. Hutton, University Heights, Ohio, assignor to Hutton Fabricating and Manufacturing Corporation, Cleveland, Ohio, a corporation of Ohio

Application October 21, 1955, Serial No. 541,920

2 Claims. (Cl. 122—499)

This invention relates, as indicated, to furnace door frames, but has reference more particularly to water-cooled door frames of the type commonly used for the door openings of open-hearth furnaces.

A primary object of the invention is to provide a door frame of the character described, which is so constructed as to effectively resist the effects of the furnace heat, particularly in the area of the door frame adjacent the corners of the arch.

Another object of the invention is to provide a door frame of the character described which has incorporated therein a novel water cooling and water distributing system, which is effective to avoid turbulence and prevent the formation of steam pockets.

A further object of the invention is to provide a door frame of the character described, having a horizontal lintel of novel and advantageous construction.

Other objects and advantages of my invention will be apparent during the course of the following description.

In the accompanying drawings forming a part of this specification and in which like numerals are employed to designate like parts throughout the same,

Fig. 1 is a front elevational view of the furnace door frame;

Fig. 2 is a cross-sectional view, taken on the line 2—2 of Fig. 1;

Fig. 3 is a cross-sectional view, taken on the line 3—3 of Fig. 1;

Fig. 4 is a cross-sectional view, taken on the line 4—4 of Fig. 1;

Fig. 5 is a fragmentary cross-sectional view, on an enlarged scale, taken on the line 5—5 of Fig. 1, and

Fig. 6 is a cross-sectional view, on an enlarged scale, taken on the line 6—6 of Fig. 1.

Referring more particularly to the drawings, the furnace door frame is of hollow construction, formed of sheet or plate steel, cut and shaped into patterned sections and united in fluid-tight welded seams.

The door frame includes a vertical lintel portion 1, from the opposite ends of which jamb portions 2 and 3 extend. The lintel portion 1 and jamb portions 2 and 3 are formed of spaced front and back plates 4 and 5, a top plate 6, side plates 7 and 8, and arch plate 9, and foot plates 10 and 11. These parts form a hollow structure, through which water may be circulated for the purpose of protecting the structure of the doorway of an open hearth furnace from the destructive effects of furnace heat.

The structure also includes a horizontal lintel, generally designated by reference numeral 12, which is adapted to underlie the skewback channel of the furnace roof. This horizontal lintel comprises a member having flat upper and lower walls 13 and 14 respectively, which are interconnected at their rear edges by an arcuate back wall 15. The ends of this member are closed by means of flat plates 16 and 17, and the lintel is connected to the plate 5 by welding the front edges of the parts 13, 14, 16

2

and 17 to the plate 5 at a position just above the level of the horizontal portion of the arch plate 9.

The structure further includes a second arch plate 18, which extends generally parallel to the arch plate 9, in spaced relation to the latter, and between the plates 4 and 5, the legs of the plate 18 terminating at points spaced from the foot plates 10 and 11.

Means have been provided for circulating water through the door frame in a novel and highly desirable manner. Such means includes a water inlet pipe 19, which extends through the top plate 6 and is curved below the plate 6, in the manner shown in Fig. 1, the pipe then extending horizontally to a point adjacent the longitudinal center of the lintel 12. At this point, the pipe is bent to provide a rearwardly extending portion 20, which passes through the back plate 5 and into the lintel 12, as best shown in Fig. 3.

The water circulates through the lintel 12 and passes out of the latter at the upper end corners thereof, as best seen in Fig. 1, through pipes 21 and 22, which extend through the back plate 5. The pipes 21 and 22 are bent to provide short vertical portions 23 and horizontal portions 24, which extend toward each other and are connected to a T 25. The water passes through the T 25 and downwardly through a short pipe 26 which is connected to the vertical branch of the T.

The pipe 26 extends through the arch plate 18, as best shown in Fig. 5, and below the pipe 26, a member 27, of inverted V-shaped cross-section is disposed, which member diverts the flow of water from the pipe 26, so that the water passes in both directions through the space between the plates 9 and 18, thence upwardly through the space between the plate 18 and plates 7 and 8, thence out of the frame through outlet pipe 28.

The flow of water is diagrammatically illustrated by the arrows in Fig. 1. The transverse cross-section of the lintel 12, combined with the fact that the water enters the lintel adjacent its longitudinal center and passes out of the lintel at the upper end corners thereof, is highly effective to avoid turbulence and prevent the formation of steam pockets.

The location of the pipes 23—24—25 within the lintel portion 1 of the door frame not only protects these pipes from the effects of the furnace heat, but provides a natural gravity flow and uniform distribution of the cooling water over the arch plate 9, so as to provide maximum cooling for this plate and adjacent parts of the door frame.

It may be noted at this point that only a single set (19 and 28) of inlet and outlet pipes is provided for the entire cooling arrangement, comprising the lintel 12 and pipes 24. This is in contradistinction to the arrangement shown in McDonnell Patent No. 2,246,403, in which two sets of inlet and outlet pipes are required.

A highly important feature of the invention resides in the use of the second arch plate 18. This plate serves a number of purposes. It not only greatly strengthens the door frame in an area where maximum strength is required, namely at the corners of the arch, but maintains the radii of these corners, preventing the jamb portions 2 and 3 of the door frame from spreading outwardly. It also serves to force a channelled flow of water against the plate 9, providing positive cooling along the entire length of this plate, and preventing burn-out of the frame at the corners of the arch. All of this results in a greatly prolonged life for the door frame.

In practice, the legs of the plate 18 terminate at points about 16 inches from the plates 10 and 11. This enables circulation of the water to continue, even should a large amount of sediment or residue of solids from the

circulating water collect in the bottom of the jamb portions 2 and 3 of the frame.

In order to permit periodic cleanout or washout of the frame, drainage openings 28 are provided adjacent the lower ends of the jamb portions 2 and 3. These openings are maintained closed during normal use of the door frame.

It is thus seen that I have provided a door frame of the character described, which admirably fulfills all of the stated objects of the invention.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a furnace door frame of the character described, front and rear plates defining, in part, a hollow structure consisting of a vertical lintel and spaced jamb portions extending from said lintel, an arch plate for closing the bottom of said frame, and a second arch plate within the hollow structure in parallel spaced relation to said first arch plate, a hollow member extending rearwardly from said rear plate and defining a horizontal lintel, means for circulating a fluid through said hollow structure and horizontal lintel, said means comprising an inlet pipe extending from one of the upper corners of said structure to a point adjacent the center of the horizontal lintel, conduits for conducting said fluid from the ends of said horizontal lintel to a common point within said vertical lintel at substantially the horizontal center thereof, said conduits extending in a forward direction and thence upwardly into the vertical lintel and thence horizontally to said common point, a conduit for conducting said fluid from said common point to said jamb portions, said last-named conduit extending through

the center of said second arch plate, whereby to divert said fluid into the space between the arch plates, and a fluid outlet pipe adjacent the other upper corner of said structure for conducting the fluid from said jamb portions to a point exteriorly of the door frame.

5 2. In a furnace door frame of the character described, front and rear plates defining, in part, a hollow structure consisting of a vertical lintel and spaced jamb portions extending from said lintel, an arch plate for closing the bottom of said frame, and a second arch plate within the hollow structure in parallel spaced relation to said first arch plate, a hollow member extending rearwardly from said rear plate and defining a horizontal lintel, means for circulating a fluid through said hollow structure and horizontal lintel, said means comprising an inlet pipe extending from one of the upper corners of said structure to a point adjacent the center of the horizontal lintel, conduits for conducting said fluid from the ends of said horizontal lintel to a common point 10 within said vertical lintel at substantially the horizontal center thereof, a conduit for conducting said fluid from said common point vertically downward through the center of said second arch plate and into the space between said arch plates, means for diverting the fluid as it enters said space whereby to cause the fluid to flow in both directions through the space between the arch plates, and a fluid outlet pipe adjacent the other upper corner of said structure for conducting the fluid from said jamb portions to a point exteriorly of the door frame.
